DISPLAY AND SHIPPING PACKAGE

J. Warren Kane, North Bergen, N. J., assignor to
 International Folding Paper Box Co., Inc.,
 North Bergen, N. J., a corporation of New
 Jersey

Application December 20, 1938, Serial No. 246,772

16 Claims. (Cl. 206—44)

This invention relates to combined shipping and display packages and to the containers or supports used in such packages, and particularly to packages for that type of stick confection or candy known as "lollipops."

The invention contemplates the provision of a package in which the sticks of the confections are adequately supported and arranged for display purposes and which, while adapted for convenient shipment and handling, may be readily and quickly displayed on a counter by the retailer without the necessity for any assembling, folding, or other operations or of any manipulation of the package or of its contents.

15 The invention further contemplates the provision of a simple shipping package adapted to be preassembled with its contents in the desired arrangement for display purposes, which package is of simple construction and, consequently, economical to manufacture and quick and easy to assemble.

The invention further contemplates the provision of means for adequately supporting a quantity of lollipops in predetermined relation and in upright positions, which means engages the lollipop sticks at spaced points to prevent disarrangement thereof, and which means also serves as a bracing means for the container, resisting yielding or collapse of the container during the shipment and handling thereof and during the insertion of the lollipop sticks thereinto.

The invention further contemplates the provision of a stick confection container including a brace which may be inexpensively manufactured, and quickly and easily folded or bent into its operative position and inserted into the container, and which provides an adequate support for the sticks of the confection, the sticks being quickly and easily insertable into the brace and held thereby for securing the lollipops in any predetermined arrangement for display purposes.

The various objects of the invention will be clear from the description which follows and from the drawings, in which:

45 Fig. 1 is a top plan view of the improved package with part of the top of the outer box removed to show the inner boxes and the lollipops held thereby.

Fig. 2 is a side elevation and partial section of 50 the same with part of the sides of the inner and outer boxes removed to show the combined bracing means for the inner boxes and supports for the sticks.

Fig. 3 is a vertical section and end view of the 55 stick-supporting and box-bracing means.

Fig. 4 is a fragmentary vertical section of a corner of the inner box showing the unstripped punchings in the top, which punchings when stripped form holes at spaced points for the passage of the sticks of the confections.

Fig. 5 is a fragmentary top view of the bent interior bracing and supporting sheet, showing the cooperating holes or unstripped punchings therein for the passage of the sticks.

Fig. 6 is a vertical section of the bracing sheet, showing the unstripped punchings therein, which when stripped form holes for the reception of the sticks of the confections.

Fig. 7 is a combined section and front elevation 15 of a modified form of the package adapted to support confections having long sticks.

Fig. 8 is a perspective view of a modified form 20 of the support and bracing sheet for the inside of the box.

In the practical embodiment of the invention shown by way of example, the complete package shown in Figs. 1 and 2 consists generally of the similar inner boxes 10 and 11, the outer box 12 and the inner box bracing sheet 13.

The inner boxes 10 and 11 are complete boxes, each made, preferably, of a single sheet of material and provided with a top 14; a bottom 15, ends 16 and 17; secured attaching flaps 18 and 19 at each extremity of each of the ends, and side 30 flaps 20 and 21 each extending from a side edge of the top 14 and adapted to be folded over the end flaps. Each of said side flaps terminates in a bendable flap as 22 inserted into the interior of the box and against the bottom 15 to removably hold the side flap in place.

In the top 14 of the inner box are made a series of rows 23, 24, 25 and 26 of unstripped punchings intended to result in holes 27, said rows and holes being so arranged as to display the lollipops 28 in 40 the required arrangement. While the holes 27 in each row are shown to be in alignment with each other, it will be understood that the holes may be arranged in any desired position to provide a suitable display design, as may be found 45 convenient or desirable.

In any case, prior to the assembly of the lollipops in their display positions in the boxes 10 and 11, the holes 27 though circumferentially cut, are incompletely formed, being substantially filled 50 by the material 29, which it is intended to remove from the top 14 to form the hole. In other words, the punchings 29 preferably are not stripped from the top but are permitted to remain in the holes 27 until they are driven therefrom during the 55

operation of forcing the lollipop sticks 30 there-through, or by a separate operation, if desired. As has been indicated, a bracing sheet 13 is arranged in the interior of each of the boxes 10 and 11. Said sheet is provided with a series of suitably spaced parallel score lines 31, 32 and 33 extending completely across or transversely of the sheet and permitting the sheet to be folded into the generally M-shaped form shown in Fig. 3. 10 The sheet may be of somewhat heavier cardboard than that from which the boxes 10 and 11 are made, and when flat and unbent, is of substantially greater length than the distance between the sides 16 and 17 of the inner box. When bent 15 into its operative form, the horizontal or plan view projection of the sheet is the same in area and shape as that of the top 14 and bottom 15.

A series of unstripped punchings intended to result in holes 34 are arranged in rows in the 20 sheet 13, similar to the rows 23, 24, 25 and 26 of the inner box, said holes 34 being preferably of about twice the diameter of the holes 27. The punchings 35 are permitted to remain in the holes 34, if desired, in the same manner as the punchings 29 are retained in the holes 27, until the lollipop sticks are each passed through a pair of corresponding and vertically aligned holes 27 and 34. To insert the sheet 13 into the inner box, the 25 rectangular sections between the score lines are bent to the proper inclination to the vertical, namely, at an angle of approximately forty-five degrees more or less and to make the distance between the end edges 36 and 37 of the sheet about the same as the distance between the ends 16 and 30 17 of the inner box. The side flap as 20 or 22 of the inner box having been opened, the sheet 13 in its M-shaped form is inserted into the box with its side edge 38 resting against one of the side flaps as 20 and its end edges 36, 37 in sprung or 35 pressed contact with the ends 17 and 16, respectively.

It will be understood that when the sheet 13 is folded, bent or corrugated, it tends to flatten out or expand back to its original flat shape and 40 length and this tendency to flatten urges the end edges 36 and 37 to move outwardly, resulting in the pressed contact with the box sides just described. The length of the sheet is such that when the sheet is inserted into the box, the bends 45 or folds at the score lines 31 and 33 are preferably in pressed contact with the box top 14, and the fold at the score line 32 is in similar pressed contact with the box bottom 15. The sheet 13 thereby forms an adequate bracing means for 50 the box top and bottom, preventing collapse or any material yielding thereof toward each other under the stresses of handling and shipment or under the pressure thereon caused by the insertion of the sticks 30 through the holes 27 and 34. 55 The top 14 is also maintained in a flat state by the bracing sheet 13, thereby preserving the good appearance of the display package when used for display purposes. Nor do any of the inclined sections of the sheet yield to any material extent 60 under the pressure of the sticks, since said sections are comparatively rigid and are braced between the box top and bottom. In the modified form of the invention shown in Figs. 7 and 8, the bracing sheet does not directly engage the box 65 top, but bracing the top through additional inserts later to be described.

Regardless of whether the punchings 29 and 35 are removed from the respective holes 27 and 34, the confections 28 may, nevertheless, be quickly 70 and easily arranged in their desired positions by

merely pressing the stick 30 thereof through said holes, the respective corresponding holes being automatically aligned when the sheet 13 is inserted into the inner box in the position described. If the punchings have not been removed, downward pressure of the stick merely displaces the punching from the hole and it drops down into the interior of the box from which it need not be removed. The hole 34 being larger than its corresponding hole 27, and the angle of 10 the various folded sections of the sheet 13 being approximately forty-five degrees, it is an easy matter to drive the stick through the hole 34 by slight pressure, thereby removing the punching 15 35, if such punching is present in the hole 34, said punching dropping into the interior of the inner box without interfering with the proper appearance of the package and without the necessity for removal of the punchings. If desired, however, the punchings may first be stripped from the 20 holes 27 and 34, making it somewhat easier to pass the stick 30 through the hole 34, since said hole is invisible in the interior of the box. The sheet sections being comparatively rigid, the sheet does not yield if the stick does not enter 25 the hole or engage the punching. Consequently, it is comparatively easy to manipulate the stick till it does pass properly through the hole 34 or until it strips the punching 35 which is removable on the application of slight pressure thereto. 30

The stick 30 contacts with the wall surrounding the hole 34 at two spaced points as 39 and 40, and cooperates with the wall surrounding the hole 27 to hold the stick in its proper vertical position without danger of its leaning backward, forward or sidewise, whereby the rows of confections in the box are maintained, until withdrawn from the box, in their proper positions to present a good appearance for display purposes. 35

The boxes 10 and 11 with the confections assembled therein, as above described, are used as 40 shipping packages as well as for display packages so that the retailer need merely set the boxes on the counter without the necessity for manipulating any of the articles or for performing any 45 folding, assembling or other operations. For shipping purposes, two boxes 10 and 11 with the confections preassembled therein in the manner hereinbefore described, are arranged with their side flaps in contact with each other, whereafter the outer cover box 12 is arranged thereover. Said box 12 is completely open at its bottom and is merely set over the confections to cover them and to also cover the exposed sides and ends of the boxes 10 and 11. The box 12 may be tied to 50 the boxes 10 and 11 by a string 41 or the like to form a shipping package, or it may be wrapped or otherwise secured thereto, if desired, it being understood that the completely assembled package, consisting of the boxes 10, 11 and 12 and 55 their contents are preferably tied together and set into larger cartons containing a plurality of such packages for purposes of shipment from place to place. The retailer receiving the package merely removes the outer box 12 whereupon the boxes 10 and 11 are exposed ready to be set on the counter for display. 60

Referring now to Fig. 7, I have there shown a modified form of the invention particularly applicable to comparatively deep boxes and confections having long sticks as 44. The outer or cover box 45 is open at its bottom and covers the inner box 46, which is deeper but otherwise similar to the boxes 10 and 11, and is similarly provided with unstripped punchings or holes 47 65 70 75

in its top 48. The bracing and supporting sheet 49 is similar to the bracing sheet 13, but does not directly engage the box top. It will be understood that to provide the required number of 5 rows of holes 50 in the sheet 49, all at about the same distance above the bottom 51, the sheet is bent about a number of parallel spaced score lines. If the sheet were high enough to engage the box top as well as the box bottom, the inclinations of the sections of said sheet would be too great, in this case, to permit easy passage of the sticks 44 through the holes 50, or said holes would have to be made of too great a diameter.

To obviate these difficulties, the angle of the 15 sheet sections to the bottom is maintained at about forty-five degrees more or less, but additional bracing inserts as 52 and 53 are arranged between the sheet 49 and the box top, so that any pressure on the top is transmitted to the 20 sheet by the inserts and transmitted by the sheet to the box ends.

The insert 53 comprises a top 54, and a pair of sides 55, 56 depending from the top and having their lower edges 59, 60 arranged in the trough 25 57 of the middle depression in the sheet 49. Preferably, the insert 53 is used to brace the top 48 until all the sticks 44 have been inserted through the corresponding vertically aligned holes in the top and the sheet, whereafter the 30 inserts 52 are inserted into place. The top 58 of the insert 52 engages the under face of the box top while the lower edges 61, 62 of the respective depending sides rest on the upper surface of an inclined section of the sheet 49 and are braced 35 against the adjacent sticks 44 against collapse. The box top is maintained substantially rigid and against yielding or collapse by the inserts co-operating with the sheet 49 in an obvious manner when the sticks are in place.

40 If desired, the insert 53 may be used as a temporary bracing means, and later removed and replaced by the permanent inserts 52, or the insert 53 may be left in place as may be found convenient. In the latter case, as shown in Fig. 8, 45 the bracing sheet may be made in one piece with the insert by the provision of additional score lines 63, 64, 65 and 66 and additional material between the score lines at the middle of the sheet to form the integral sides 67, 68 and the connecting top 69.

It will be seen that the invention provides a simple, economical and efficient combined display and shipping package well adapted to meet the severe requirements of practical use and designed to adequately support and display a large 55 number of confections pleasingly and conveniently.

While I have shown and described certain specific embodiments of my invention, I do not 60 wish to be understood as limiting myself thereto, but intend to claim the invention as broadly as may be permitted by the state of the prior art and the scope of the appended claims.

I claim:

65 1. The combination with a box having a top, bottom, ends and a movable side flap closure, the top having spaced apertures therein, of an interior bracing and article supporting sheet loosely inserted into the box through an open side 70 thereof with the end edges of the sheet in engagement with the ends of the box, said sheet having parallel spaced transverse score lines therein and having a plurality of apertures between the score lines each of greater diameter than that of the 75 apertures in the top, said sheet being bent on said

score lines into M-shaped form to provide flat and comparatively rigid inclined sections between the score lines, each of said sections extending between and being in contact with the top and bottom of the box, corresponding apertures in the 5 top and in said sheet being in vertical alignment to permit the vertical passage of the stick of a stick confection therethrough with the end of the stick in contact with the bottom.

2. In a combined display and shipping package 10 for lollipops, a pair of similar boxes each having apertures in the top thereof, a bracing sheet within each box provided with apertures in vertical alignment with, and of greater diameter than, the apertures in the top of the box, the 15 bracing sheet being bent along spaced parallel score lines to provide a multiplicity of angularly arranged sections thereon separated by folds and to impart a flattening tendency thereto, the ends of said sheet contacting with the ends of the 20 box and the alternate folds contacting with the top and bottom of the box respectively, said boxes being arranged in side to side contact, a plurality of lollipops each provided with a stick, the stick of each lollipop being passed through 25 an aperture in the top of a box and through a corresponding aligned aperture of the sheet, and an outer box open at its bottom and having a closed top resting on the lollipops.

3. A combined shipping and display package 30 for confections each provided with a stick, comprising a pair of boxes arranged in side by side relation and each having an apertured top, an apertured bent bracing sheet within the box, the stick of each confection passing through an aperture of the top and a corresponding aperture of the sheet, an outer covering box open at its bottom and having a top resting on the confections, and means for detachably securing the boxes together whereby removal of the covering box exposes the first-mentioned pair of boxes for display.

4. A combined shipping and display box for stick confections comprising a box having an apertured top, and a bracing sheet having spaced 45 parallel score lines completely thereacross and having apertures therein of larger diameter than the apertures of said top, said sheet being loosely inserted into the box with the apertures thereof in vertical alignment with the corresponding 50 apertures of the top and with the ends thereof braced against the ends of the box, said sheet being bent about said score lines in position to arrange the material at alternate lines in pressed contact with the inner face of the top of the box 55 and to arrange the material at the remaining score lines in contact with the bottom of the box, the sections of the sheet between the score lines being each arranged in an inclined position.

5. A combined shipping and display box comprising a box having a top, bottom, sides and ends, the top having a plurality of apertures of one size therein, and a combined bracing and supporting sheet loosely inserted within the box and coextensive therewith, said sheet having 60 apertures of a larger size therein each vertically aligned with an aperture of the box top, said sheet being bent along parallel lines to provide angularly disposed sections on said sheet extending between and contacting with the top and 65 bottom of the box, the end edges of said sheet being braced against the ends of the box, and at least one of the sides of the box being openable for the insertion therethrough and into the box 70 of said sheet.

6. The combination with a box having an apertured top, of a combined bracing and supporting sheet having an area greater than that of said top, said sheet having apertures therein corresponding to and aligned with but larger than the apertures of the top, said sheet being bent into angularly arranged sections along transverse parallel lines and being fitted slidably into the box with the end edges thereof braced against the ends of the box, said sections extending angularly and rigidly between and bracing the top and bottom of the box.
7. The combination with a box having an apertured top, and having a bottom, sides and ends, of a bracing and supporting sheet loosely inserted into the box with the end edges thereof braced against the ends of the box, said sheet being apertured correspondingly to the apertured top, and said sheet being of generally M-shaped form to provide a series of flat and comparatively rigid inclined transverse sections therein extending between and bracing the box top and bottom and in contact therewith.
8. A box having a perforated top, and means for bracing the top and for also cooperating with the top to support stick confections including a perforated sheet arranged loosely in the interior of the box and extending between a pair of opposed faces thereof, said sheet being bent along the transverse parallel lines into a plurality of inclined perforated sections, the respective perforations of the sections which correspond to the perforations of the top being in substantial vertical alignment.
9. A box having a perforated top and means for bracing the top and for also cooperating with the top to support stick confections, said means including a sheet loosely arranged in the interior of the box and engaging the box at its end edges, said sheet having a plurality of sections therein each bent into a position inclined at an angle other than a right angle to the box top and each perforated correspondingly to the top with perforations of greater diameter than those of the top.
10. A box having a perforated top and means for bracing the top and for also cooperating with the top to support stick confections, said means including a first sheet loosely arranged in the interior of the box and engaging the box at its end edges, said sheet having a plurality of sections therein each bent into a position inclined at an angle other than a right angle to the box top and each perforated correspondingly to the top, and an additional bracing sheet cooperating with the first sheet to brace the top, said additional sheet having a pair of sides joined by a top, the bottom edges of the sides engaging the first sheet and the top of the additional sheet engaging the box top.
11. A box having a top provided with apertures for the vertical passage therethrough of the sticks of stick confections, a bracing sheet in the

box having sections inclined to the top and provided with apertures corresponding to those in the top for the passage therethrough of the lower parts of said sticks, and bracing inserts in the box each having a top and depending sides, the top engaging the box top and the sides being arranged in position to engage the sticks with the lowermost edges of said sides engaging the inclined sections of the bracing sheet.

12. A box having an apertured top, a bracing sheet having inclined apertured sections inclined to the top, said sheet being loosely inserted into the box and held at its end edges by the box against distortion, said sections being of lesser height than that of the box, and bracing members interposed between and engaging the box top and the bracing sheet and transmitting stresses therethrough from the box top to the sheet and thereby bracing the top against yielding and collapse.

13. A box having an apertured top, a bracing sheet in the box having apertured sections inclined to the top, and bracing members in the box resting on the sheet and engaging the box top.

14. A box having a perforated top and having imperforate sides, ends and a bottom, and a sheet arranged in the interior of the box and bent along transverse parallel lines into inclined substantially rigid triangular sections extending between and bracing the box top and bottom and in contact therewith, said sheet being perforated correspondingly to the perforated top, and the end edges of the sheet being in pressed contact with the box ends.

15. A box provided with a top having unstripped punchings therein adapted to be stripped therefrom to form apertures in said top, and a sheet within the box having corresponding unstripped punchings therein of larger diameter than those of the top, said sheet being bent into inclined substantially rigid triangular sections extending between and bracing the box top and bottom and in contact therewith, said punchings being strippable from the top and sheet by the pressure of the stick of a stick confection.

16. A box provided with a top having unstripped punchings therein adapted to be stripped therefrom to form apertures in said top, said box having imperforate sides, ends and a bottom, and a sheet within the box having corresponding unstripped punchings therein of larger diameter than those of the top, said sheet being bent along transverse lines into inclined substantially rigid triangular sections each extending between and contacting with the box top and bottom, the end edges of the sheet being in pressed contact with the box ends, said punchings being strippable from the top and the sheet by manual pressure applied thereto by the stick of a stick confection, said stick being supported in vertical position by the walls of the apertures produced by the stripping of the punchings.

J. WARREN KANE.
